DESIGN FOR A SPRING TESTING MACHINE

James D. Burke, Los Angeles, Calif., assignor to
A. Morgan Maree, Jr., Speed L. Post, Stanley E.
Lindahl, and James D. Burke, all of Los Angeles,
Calif., as tenants in common

Application September 1, 1945, Serial No. 121,794

Term of patent 14 years

(Cl. D52—1)

To all whom it may concern:

Be it known that I, James D. Burke, a citizen of the United States of America, residing in the city of Los Angeles, in the county of Los Angeles, State of California, have invented a new, original, and ornamental Design for a Spring Testing Machine, of which the following is a specification, reference being had to the accompanying drawings, forming a part thereof.

Figure 1 is a plan view of a spring testing machine showing my new design;

Figure 2 is a front elevational view of said machine;

Figure 3 is a left end view of the same; and

Figure 4 is a right end view of said testing machine.

I claim:

The ornamental design for a spring testing machine, substantially as shown.

JAMES D. BURKE.
